UNITED STATES PATENT OFFICE

JOSEPH NOLL, OF BUFFALO, NEW YORK, ASSIGNOR TO CONRAD HAMMER, OF BUFFALO,
NEW YORK.

BOTTLE-HOLDER.

1,021,328.

Specification of Letters Patent. Patented Mar. 26, 1912.

Application filed March 13, 1911. Serial No. 614,093.

To all whom it may concern:

Be it known that I, JOSEPH NOLL, a citizen of the United States, and resident of Buffalo, in the county of Erie and State of New 5 York, have invented new and useful Improvements in Bottle-Holders, of which the following is a specification.

My invention relates to bottle holders and more particularly to a holder used in connection with or embodied in a bottle washing apparatus.

In some forms of bottle washing apparatus the bottles to be washed are placed over a tube from which the water flows to 15 cleanse the interior of the bottle, and in some instances, these tubes during the operation of the apparatus assume various positions; for example, at times they assume an upright position, and at other times a depending position, and in moving from the upright to the depending position, they travel through an arc of a circle and consequently assume changing positions.

The primary object of my invention therefore is, to provide bottle holding means which will effectively hold a bottle in position on a water discharge tube regardless of the position said tube may be in and to prevent lateral movement of the bottles on 30 the tube.

Another object of my invention is, to provide means for effectively holding the bottles on the water discharge tube and at the same time permit the neck labels, such as 35 are used on beer bottles and other forms of bottles, to be loosened from the neck of the bottle and washed away.

Another object is, to so construct the bottle holding device that bottles can be quickly 40 placed over the water discharge tubes and removed therefrom without liability of becoming cracked or chipped, particularly at the edge of the bottle where the cork, cap or other closure is applied.

45 Further objects are, to provide improved means for limiting the extent to which the bottles can be thrust into the holding device and to otherwise improve on devices of this character now in use.

50 With these and other objects in view, the invention consists in the arrangement of parts and in the construction and combina-

tion of devices and parts as will be herein-after described and more particularly pointed out in the subjoined claims.

55 In the drawings in which similar figures of reference refer to corresponding parts in the several figures, Figure 1 is a side elevation of my improved holder showing the same in representative form applied to a 60 part of the bottle washing apparatus and showing in dotted lines the manner of supporting and holding a bottle in position to be washed. Fig. 2 is a similar view showing the bottle in a different position. Fig. 65 3 is a cross section taken on line $x-x$, Fig. 1. Fig. 4 is a cross section taken on line $y-y$, Fig. 1. Fig. 5 is a vertical section taken on line $z-z$, Fig. 4.

70 Reference numeral 6 designates a part of a bottle washing apparatus having a water feed tube 7 from which projects the water discharge tube 8. It is to be understood that the tube 7 is of considerable length and has or may have a number of water discharge tubes, such as 8, connected therewith and that this water feed tube may be movable or stationary and that any other form of water supply may be substituted therefor.

75 My improved holder is adjustably and removably secured to the water discharge tube 8, so that bottles having necks of different lengths may be accommodated or so that holders of different size or shape may be substituted when washing bottles having a 80 neck and body of different contour than that herein shown.

85 The holder comprises essentially a head 9, and a plurality of holding arms 10. Said head is constructed with a hub 11 fitting 90 onto the water discharge tube and having a set screw 12 threaded therethrough and impinging against the said tube so as to permit of fastening the head at any point in the length of the tube and a plurality of 95 lugs 13 corresponding in number to the number of holding arms used, each lug having a pair of upstanding ears 14 and a depression 15 in its upper face for a purpose to presently appear.

100 In the illustration shown, there are three holding arms, which I deem sufficient for ordinary purposes. These arms extend upward from the head 9 and have their lower

ends positioned between the several pairs of ears 14 and pivoted thereto by a pivot pin 16. Each arm has an angular toe or extension 17 at its lower end, between which and 5 the coöperating lug 13, a spiral spring 18 is interposed, one of the ends of these springs being seated in the depressions 15 formed in said lugs and the other bearing against the under or inner sides of said toes 10 or extensions and acting thereagainst to yieldingly hold the bottle holding arms against the water discharge tube 8 or against the neck of a bottle when placed over said tube. The said angular toes or extensions 15 project from the outer edges of said holding arms and at the inner edges of said arms, extensions or shoulders 19 are provided which serve as abutments for the open end of the bottle when thrust between said arms. 20 Each of the holding arms is formed with two contact protuberances or prominences 20 at its inner edge and between these points it is curved or otherwise shaped to provide a clearance space 21 between the arms and 25 the neck of the bottles when thrust between said arms. This permits the label on the neck of the bottle to be thoroughly soaked and in passing through the washing apparatus or by treatment otherwise, it will be 30 washed from the neck. These contact points 20 offer resistance to the introduction of a bottle between the holding arms so that with the springs acting to yieldingly hold the arms inward, it will be impossible to force 35 the open end of a bottle against the abutments 19 with sufficient force to crack or chip the same; and as the free ends of the holding arms are curved outward to provide flaring inner edges at such ends, it is 40 clear that the operator needs only to grasp the bottle, place the open end thereof over the end of the water discharge tube and against the inner edges of the holding arms, then force the bottle down until the open 45 end contacts with the abutments. When forcing the bottle down the upper or outer contact or resistance points first impinge against the neck of the bottle and offer resistance to the same, and when the lower or 50 inner set of contact or resistance points are engaged by the open end of the bottle, the holding arms are caused to move outward farther and in some instances, depending on the shape of the bottle neck, the upper 55 or outer set of contacts or resistance points are momentarily forced out of contact with the neck of the bottle. The necessary resistance, however, is applied to the bottle by the lower set of contacts so that after 60 passing the last named contacts, the bottle is gradually moved down against the abutments 19 and when in this position, both the upper or outer and the lower or inner sets of

contact points impinge against the bottle and effectively hold the same centrally over 65 the tube 8.

It is to be understood that the resistance offered to the introduction of the bottle neck between the holding arms is not sufficient to render it difficult to position the bottle, but merely prevents sudden and forcible contact of the open end of the bottle against the abutment. It is apparent also that for bottles of different shapes or contour, the holding arms herein shown may not serve to 70 properly hold the bottle in position and in such cases a holder is applied to the water outlet tube 8 which will be formed in shape, or length to properly grasp the neck of the bottle, or if desired, both the neck and body, 75 as this would be merely a matter of design so long as the features of my invention are retained; and it is furthermore apparent that changes in the construction and arrangement of parts may be resorted to without 80 departing from the spirit of my invention or sacrificing any of the advantages thereof. 85

Having thus described my invention, what I claim is,—

1. A bottle holder having a plurality of 90 stiff radially movable pivoted arms adapted to grasp the neck of a bottle and provided with two sets of inwardly projecting contact points offering resistance to the introduction of the bottle between said arms and a set of abutments on said arms against which the open end of the bottle is to be held.

2. A bottle holder comprising a head having a plurality of outstanding lugs and each 100 lug having a pair of spaced ears, a bottle holding arm pivotally secured between each pair of ears and having an outstanding toe adjacent its pivotal point, and springs interposed between said toes and said lugs to 105 force said arms inward.

3. A bottle holder comprising a head having a plurality of outstanding lugs, each provided with a depression in its upper face and with a pair of spaced ears, a bottle 110 holding arm having one end pivotally secured between each pair of said ears and provided with an angular toe projecting from the outer edge thereof, and springs held at one of their ends in the depressions 115 of said lugs and bearing at their other ends against said angular toes to force the bottle holding arms inward.

4. A bottle holder having a support and a plurality of radially movable arms pivotally secured to said support, each of said arms having prominences and an abutment at its inner edge, as and for the purpose set forth.

5. A bottle holder comprising a head, a 125 plurality of bottle holding arms pivotally

secured to said head and having their inner edges flared at their outer ends, each arm having two spaced inwardly projecting contact points between its extremities and an abutment between the inner contact point and the pivot of said arm, corresponding contact points on said arms acting in unison to grasp a bottle.

In testimony whereof, I have affixed my signature in the presence of two subscribing 10 witnesses.

JOSEPH NOLL.
